CLAIM

The ornamental design for an RFID tag as shown and described.

DESCRIPTION

FIG. 1 is an isometric view of an RFID tag in accordance with the design;

FIG. 2 is a top plan view thereof, with portions shown in exploded detail in FIGS. 3-5;

FIG. 3 is an enlarged top perspective view of FIG. 2;

FIG. 4 is an enlarged top perspective view of FIG. 2; and,

FIG. 5 is an enlarged top perspective view of FIG. 2.

The broken lines indicating where the enlargements have been taken form no part of the claimed design.

1 Claim, 4 Drawing Sheets(56)
